(57) **CLAIM**

The ornamental design for a pass through grilling mechanism, as shown and described.

DESCRIPTION

FIG. 1 is a perspective of a pass through grilling mechanism; FIG. 2 is a front view of the pass through grilling mechanism;

FIG. 3 is a rear view of the pass through grilling mechanism; FIG. 4 is a right side view of the pass through grilling mechanism;

FIG. 5 is a left side view of the pass through grilling mechanism;

FIG. 6 is a bottom view of the pass through grilling mechanism; and,

FIG. 7 is a top view of the pass through grilling mechanism.
